BERNHARD LEVINE, OF BRONX, NEW YORK

BOOKMAKING MACHINE ATTACHMENT

Application filed June 6, 1932. Serial No. 615,521.

This invention relates to an improvement in a machine used in making or binding books. It relates particularly to an attachment that is especially useful in connection with a machine known in the book binding art as Smythe #3 sewing machine.

In making up books a number of so-called signatures is ordinarily assembled and sewed together to be held securely in place and permit the leaves of the book to open. In assembling and sewing the signatures machines are used by means of which holes are first punched through the individual signatures for the sewing needles to enter. In such machines now in common use the signatures are held upon an arm that is supported at only one end and the reaction caused by forcing the punches through the paper while it is pressed against a member to hold the paper causes a considerable reaction thrust which not only often causes the free end of the arms to sag, but sometimes breaks the arms or support therefor. When the arms carrying the signatures sag at one end the punches do not operate effectively but produce the holes so that the sewing needles are often broken.

One of the objects of this invention is to remedy this trouble and securely hold the signature supporting arms securely in position while the punches punch appropriate holes through the folds of the signature, without interfering in any way with the normal operation of the machine. This is accomplished by causing a supporting cam to move into position to support the free end of the signature-carrying arm during the time the holes are being punched through the paper.

The invention will be understood from the description in connection with the accompanying drawing in which Fig. 1 is an elevation of a portion of a #3 Smythe sewing machine that is used in the book-binding art; Fig. 2 is a similar view on an enlarged scale, partly broken away and partly in section; Fig. 3 is a section along the line 3—3 of Fig. 2, and Fig. 4 is a section along the line 4—4 of Fig. 2.

In the drawing reference character 1 in-

dicates a portion of the frame of a well-known machine that is used in making or binding books. The machine is provided with a plate 2 through which needles (not shown) are operated for sewing signatures after punches have punched the holes there-in for this purpose. This plate also serves as a stop or rest against which the signatures are pressed while the holes are being punched through them.

A vertical shaft 3 is journaled in bearings 4 on the frame of the machine 1. Arms 5 for supporting book signatures are revoluble around the shaft 3 and are movable into place beneath the plate 2 while needle or thread holes are being punched through the folded portions of the signatures that are supported on the upper edges of the arms. A set of vertically movable punches 6 is carried by each arm 5 varying in number according to the number of holes that are to be punched through the book signatures.

A hub 7 is journaled on the shaft 3 to which one end of each arm 5 is attached leaving the other ends of the arms free. Mechanism is used for automatically lowering the hub 7 on the shaft 3 and turning it a pre-determined amount at intervals and again raising it in regular sequence. The respective arms 5 are thus moved into position to receive the signatures with the folds thereof resting upon the upper edges of the arms, then these arms are moved one after the other into place beneath the plate 2 where the holes are punched by the punches 6 and are then lowered and moved into position where the punched signatures are removed and the arms are ready to receive fresh signatures and carry them into place to be punched by the punches 6. This mechanism is well-known and as it constitutes no portion of this invention, only a small portion of it is indicated at 8.

The punches 6 of each arm 5 are moved upwardly when the arm is below the plate 2 by a sliding cam 9 carried by it having cam grooves 10 for rollers 11 in the arm. This cam 9 is moved longitudinally by mechanism connected to its end 12 and is operated in synchronism with the operation of the hub 100

7, thus raising the punch-carrying bar 13 vertically and causing the punches 6 to punch holes at the folds of the signature which is at that moment between the upper edge of the arm 5 and the bottom of the plate 2. The plate 2 is provided with holes along its lower portion into which the ends of the punches 6 may enter after they have passed through the signatures. The mechanism for operating the cam 9 at the proper moment is also old and well-known and therefore it is unnecessary to describe it more in detail as it forms no part of this invention. This mechanism withdraws the punches 6 at the proper instant by moving the cams 9 to the right after the holes have been punched.

When each arm is being raised into position below the plate 2 its outer end 15 enters a groove 16 having an entrance guide arm 16'. The groove 16 is provided for the end of the arm 5 in a plate 17 that is attached to the frame 1 by screws 18. A stop 19 is provided at the upper end of the groove 17 which is struck by the upper edge of the end 15 of the arm 5 when it is in its uppermost position.

The parts thus far described are all old and machines of this sort are in extensive use. A serious difficulty has arisen in such machines because when the cams 9 are moved to the left to cause the punches 6 to punch the holes the right-hand end of the arm 5 is apt to sag down, especially when thick signatures or signatures of tough paper are being punched. By the present invention this difficulty is completely overcome in a very simple and inexpensive manner by a device that is operated in synchronism with the movement of the other parts of the machine. The improvement comprises a guide member 20 that is attached to the frame 1 by screws 21, or in any other convenient way. The guide member 20 has a longitudinal opening 22 therethrough for supporting a support 23 that is slidable in the opening 22 and is provided with a bevel end or cam 24 which is moved under the end of each arm 15 at the proper moment. An opening 25 is provided through the plate 17 in the upper portion of the groove 16 through which the end of the support 23 passes.

A link 26 connects the support 23 to one end of a lever 27 that is pivoted on the frame 1 at 28. The other end of the lever 27 is connected by a link 29 to one end of the bell crank 30 that is pivoted at 31 on the machine. The other end of the bell crank 30 carries a roller 32 journalled on a pin which extends into a cam groove 33 on a cam 34 that is journalled in bearings on a bracket 35 attached to the frame of the machine and driven by gears that drive the mechanism 8 and the mechanism for moving the cam 9

back and forth so that the parts will move in proper sequence.

In the operation of the machine a signature is placed upon an arm 5 while it is in its lowermost position and extending at right angles to the position of the complete arm shown in Fig. 1. The mechanism 8 turns the arm 90° and then raises it with its end 15 passing upwardly in the groove 16 to the position shown in Fig. 1. The portion 33' of the cam groove 33 at that moment reaches the pin 32 on the lever 30 and thereby causes the link 29, lever 27 and link 26 to move the support 23 to the left into the position shown in Fig. 1 with the upper edge of this support resting under the lower edge of the outer end 15 of the arm 5. The sloping end 24 or cam facilitates entry of the end of the support 23 under the end 15 and prevents it from being forced away from the plate 2 so long as the support 23 is in position. The mechanism for pushing the cam 9 to the left then performs its function, thus pushing the punches 6 up into the position shown in Fig. 1 to punch the holes through the signature. Due to the presence of the support 23 below the end 15 of the arm 5 the danger of the end of this arm sagging downwardly because of the reaction of the punches against the signature or paper that is pressed against the lower side of the plate 2 is obviated. As soon as the holes have been punched by the punches 6 the cam 9 is moved to the right to withdraw the punches from the holes and at the same time the cam 34 moves the support 23 to withdraw it from below the end 15 of the arm 5, whereupon this arm is caused to descend to a position below the lower end of the plate 17 and is then moved circumferentially around the shaft 3 while the next arm carrying a signature is moved into position and the same operation takes place.

I claim:

1. In a book making machine having a supporting frame and a laterally movable arm supported at one end for book signatures and carrying punches for making holes for needles through the signatures, a support on said frame for the free end of said arm, and means to move said support into position prior to the operation of said punches.

2. In a book making machine having a laterally movable arm supported at one end for book signatures and carrying punches for making holes for needles through the signatures, a support comprising a reciprocating member for the free end of said arm, and means to move said support into position prior to the operation of said punches.

3. In a book making machine having a laterally movable arm supported at one end for book signatures and carrying punches for making holes for needles through the signatures, a support comprising a recipro-

cating member for the free end of said arm movable substantially parallel to said arm, and means to move said support into position prior to the operation of said punches.

5 4. In a book making machine having a laterally movable arm supported at one end for book signatures and carrying punches for making holes for needles through the signatures, a support having a cam thereon
10 for the free end of said arm, and means to move said support into position prior to the operation of said punches.

15 5. In a device of the character described in which a swinging book signature carrying member is provided with punches and is subjected to a reaction thrust when said punches are operated, a longitudinally reciprocating thrust resisting member movable into place to sustain said reaction thrust
20 and movable out of place to permit said swinging member to move.

25 6. In a device of the character described having a frame and a swinging book signature carrying member which is provided with punches and is subjected to a reaction thrust when said punches are operated, a thrust resisting member supported on said frame, and a cam and connections supported on said frame for operating said thrust
30 resisting member.
